John O'Neil

UNITED STATES PATENT OFFICE.

JOHN O. NASLIN, OF SEATTLE, WASHINGTON.

DOOR-CLOSING DEVICE.

1,318,903.

Specification of Letters Patent. Patented Oct. 14, 1919.

Application filed June 17, 1918. Serial No. 240,561.

To all whom it may concern:

Be it known that I, JOHN O. NASLIN, a citizen of the United States, residing at Seattle, in the county of King, State of Washington, have invented a new and useful Door-Closing Device; and I do hereby declare that the following is a full and exact description thereof, reference being had to the accompanying drawings and to the characters of reference marked thereon.

My invention relates to a door closer, by the action of which the door is rendered self-closing, and in addition to being durable and very simple in construction, will 15 at the same time close a door, and the like, if properly constructed and applied, in such a manner that the old time annoyance of slamming will be almost entirely eliminated; and can also be adjusted so as to 20 increase, decrease and check, and again increase the closing movement of the door before it reaches a closed position, and will hold it closed.

I attain these objects by the mechanism 25 illustrated in the accompanying drawings, wherein—

Figure 1 is a plan view of the door closer, as it appears when the door is closed, with the housing shield swung to the side, and 30 the regulating members exposed to view; "1" representing the door, "2" the head casing, "3" the jamb, "4" the wall and "5" the hinge of the door.

Fig. 2 is also a plan view of the door 35 closer, as it appears when the door is swung to a square position with the wall.

Fig. 3 is a longitudinal vertical section of arm or link A, viewed from the side, and in which is seen the position of the regulating 40 members.

Fig. 4 is a side view of arm B, and

Figs. 5 and 6 are additional plan views of the door closer, as it appears when attached to the side of the door, opposite to 45 that shown in Figs. 1 and 2; in Fig. 5, the door is closed, and in Fig. 6, it is swung open to a square position with the wall.

In these figures the same letters and numbers refer to the same parts.

50 The device can be used for any kinds of doors and gates, or the like, for either right or left hand swinging doors, and on either side if desired.

The two bars forming the hollow structure, designated by letter A, providing 55 room for the tension and regulating mem-

bers, as shown in Fig. 3, are depressed at the ends so as to meet and form a horizontal clamp joint with bearing bracket C, upon the vertical bolt axis K, and also in like manner, meet and form a union with the convergent end of arm B, upon bolt axis M; the opposite bifurcated end of arm B, forms in like manner a detachable joint with bracket D, upon bolt axis L. By these 65 bolts, which are provided with heads and screw-threads with nuts, the said joints are properly held in operative order, and can readily be adjusted, by loosening or tightening, as may be required.

When the device is used on the side of a door, as indicated in Figs. 1 and 2, bearing bracket C should be fastened onto the head casing "2", and bearing bracket D should be fastened onto the door at its 70 upper edge; but when the device is used on the side of a door, as indicated in Figs. 5 and 6, bracket C with arm A should be fastened onto the door, and the divergent end of arm B should be pivoted to the under 75 side of the head piece of the door jamb.

Whether bracket C is fastened onto the head casing "2" higher up than bracket D, which in the present case I have fastened onto the door at its upper edge, just high 80 enough so that arm B, which is jointed thereto with its forked end, upon bolt axis L, can swing clear of the top edge of the door, from which it is deflecting upward until it forms a union with arm A, upon 85 bolt axis M, on a horizontal line with bracket C; or both of these brackets are set on a horizontal line with each other, in which case arm B need not be deflected in alignment as shown in Fig. 4, it is, however, 90 essential that the construction, positions and adjustments of both these brackets and arms be such, as to permit of the free and 95 normal movement of the door, or hinged element.

The lateral deflection in arm B, near its convergent end, forms an open space wherein the forked end of pendant F may be 100 freely turned upon pin P, when inserted in that proximity in one or another of 105 holes 1 to 7, provided on a concentric line about bolt axis M, in sector E; which in turn is mounted and rigidly secured by means of clamp-screw E², upon said arm B, with which it forms a union upon bolt 110 axis M; and therefore can readily be detached and again replaced, and used for

either right or left hand purposes. It is, however, manifest that, if bracket C were in line with bracket D, this deflection in arm B would be superfluous, nor would 5 sector E need to be detachable from arm B, but could then be an integral part thereof, as said arm B and sector E, could then be used for either right or left hand purposes, by merely being turned over one way 10 or another to suit conditions.

From the foregoing it will be seen that, when the door is swung open from the closed position in Fig. 1 to the open position in Fig. 2, the horizontally jointed arms A—B, 15 relatively spread about axis M; and it is this relative spreading, in combination with pendant F, and the consequent tension of spring G, which is essential and is utilized for the operation of automatically closing 20 the door. For this purpose spring G, must be of suitable length, tension and size, and, therefor has been provided at one end with an adjustable connection, consisting of a rod-hook N, screw-threaded with nut at one 25 end, extending some distance into the spring, and at the other end is shaped into a suitable hook, to be attached in one or another of holes 1 to 5 in bracket C, while the opposite end of said spring is merely shaped into 30 a hook, by which it may be attached to aperture O, provided in what will be termed the floating speed-regulating pendant F, which at one end is adapted for adjustable axis connection, as by means of pin P, in- 35 sertible in one or another of holes 1 to 7, provided in sector E, on a concentric line about axis M, of the union of arms A—B.

The swinging end of pendant F is shown as reaching a considerable distance beyond 40 aperture O therein, and is otherwise adapted at that end to form a groove-abutment, as at Q, against which a portion of spring G will press, when said pendant F by proper connections and adjustments assumes cer- 45 tain positions, as elsewhere described, during the relative movements of the door and arms A—B.

Said pendant F, besides being adapted to swing on pin P, and forked at that end to 50 straddle sector E, is curved and shaped so that it may not come in contact with the union of arms A—B at M, when the door is swung open, and to be guided and kept in proper position when the door swings back 55 on its closing course. It forms at the other edge a dent-abutment, as at T, against which adjusting striker J, at a certain instant of the closing movement of the door will strike and press pendant F and spring G to the 60 side, as indicated in Fig. 1.

Said striker has at I, a screw-threaded 65 passage through arm B, nut J¹ and collar-hold E¹, extending at that point from sector E; which together with the other regulating

means for closing the door, the important means for regulating and controlling its closing movements, or if so desired, to check its movements entirely.

For this purpose I have provided the said 70 adjusting striker J, which has the function to strike its inward pointing end against the adjacent abutment T, of pendant F, as the door swings from the open position in Fig. 2, wherein it is seen that said striker 75 J, having engaged pendant F, causes the latter to move across the direct line between pin P and the connecting point of spring G in bracket C; thus, to some extent for a short distance, checking the closing move- 80 ment of the door. While, as the door slowly moves on and the position of arms A—B change, the tension and directing force of spring G also become changed, and increases, so that the movement of the door again in- 85 creases more and more until it reaches a closed position, as indicated in Fig. 1. The farther the pendant is pressed in that manner, the greater will the resistance of the device be to the closing movement of the door. 90

Furthermore, spring G can otherwise be adjusted so as to exert a stronger or weaker pulling effect upon the closing movement of the door, while swinging from the position in Fig. 2, until the end of striker J encoun- 95 ters pendant F, which until this instant swings freely about pin axis P, while the tension of the spring uninterruptedly moves the opened door on its closing course; where- 100 fore, with proper adjustment of said spring G, by the insertion of hook N in one or another of holes 1 to 5 in bracket C, and the attachment of pendant F by pin P in one or another of holes 1 to 7 in sector E, the closing movement of the door can, to some ex- 105 tent, be increased, decreased and, when wide open, even be checked to a stand-still; but after the instant striker J encounters pend- 110 ant F, its closing movement is wholly con- trolled by the latter, if properly adjusted by 110 the means specified.

From which it may be clearly understood, how readily by these means, the closing movement of the door can be regulated and controlled, according to the weight and di- 115 mension of the door.

The door closer can be used for either right or left hand swinging doors, and on either side, by merely separating and again combining the several parts, as may be re- 120 quired.

For the purpose of shielding and protect- 125 ing the several parts from view and injury, particularly that of arm A, which is con- structed in two parts, one passing under and one over the tension device, but united at each end, I have provided a suitable housing shield H, covering arm A, except the side facing arm B, and adapted to be held in place at one end by means of bolt axis K, 130

and at the other end suitably adapted to be slid in place sidewise, it having transverse slits in each side, which are depressed so as to enter under the nut and head of axis M, 5 with which it is held in place; and can therefore, readily be loosened and swung to one side, as shown in Fig. 1, and again re-placed when required.

What I claim is:

10 1. In a door closer and check, a movable member and a stationary member, a swinging arm carried by said movable member, a second swinging arm carried by said stationary member, a pivot securing the free 15 ends of said arms together, a sector carried by one of said arms, a pendant pivotally connected to said sector, a spring connecting said pendant and one of said members, and means carried by one of said arms for 20 limiting the movement of said pendant with respect to one of said arms.

2. In a door closer and check, a movable member and a stationary member, a swinging arm carried by said movable member, 25 a swinging arm carried by said stationary member, a pivot securing the free ends of said arms together, means on one of said arms supporting a pendant, a spring connecting said pendant and one of said members, and means for limiting the movement 30 of said pendant with respect to said means carried by one of said arms.

3. In a door closer and check, a stationary member and a movable member, a pair of 35 pivoted arms, connected at their free ends to said members, means on one of said arms for supporting a pendant, a pendant, spring means connecting said pendant and one of said members, and means carried by one of 40 said arms for engaging the said pendant whereby the said spring means is flexed to check the motion of said movable member.

4. In a door closer and check, a hinged movable part and a stationary part, a pair 45 of swinging arms having their divergent ends respectively jointed, one to the said hinged part and the other to the said stationary part, means for attaching their divergent ends to said parts and for securing 50 their convergent ends together, a spring adjustably connected to one of said parts, a sector carried by one of said arms for adjustable pendant connection, a pendant connecting said spring and sector, and a striker 55 adjustably disposed from one of said arms

to engage and press the said pendant and spring sidewise so as to limit the tension with respect to said hinged part.

5. In a door closer and check, a hinged movable part and a stationary part, a pair 60 of jointed arms having their parted ends respectively jointed, one to the said hinged part and the other to the said stationary part, a variable sector carried by one of said arms, a pendant adjustably connected at one end to said sector, and a spring adjustably connecting said pendant to one of said parts whereby the hinged part can be rendered self-closing and varied in motion; and means carried by one of said arms for en- 65 gaging the said pendant so as to limit the closing movement of the said hinged part.

6. In a door closer and check, a hinged movable part and a stationary part, a spring-housing swinging member and a de- 70 flected swinging member, means for attaching the divergent ends of said members to the said parts and for securing their convergent ends together, a sector adapted on said deflected member for varied pendant 75 connection, a spring adjustably connected to one of said parts, a pendant connecting said spring and sector whereby the said hinged part can be rendered self-closing and varied in motion, and a striker adjust- 80 ably disposed from said deflected member whereby to engage the said pendant and limit the movement of the said hinged part.

7. In a door closer and check, a hinged movable part and a stationary part, a pair 90 of swinging arms, means for attaching the divergent ends of said arms to said parts and for securing their convergent ends together, means on one of said arms for pendant connection, a pendant connected to said means, a spring connected at one end to said pendant and at the other end adjustably connected to one of said parts, whereby the hinged part can be rendered self-closing and varied in motion, and means disposed from 95 one of said arms for engaging the said pendant and limit the movement of the said hinged part; and a detachable housing shield carried by said arms, inclosing the said spring and pendant.

JOHN O. NASLIN.
